UNITED STATES PATENT OFFICE.

DANIEL T. FOX, OF INDEPENDENCE, KANSAS.

INVALID-BED.

SPECIFICATION forming part of Letters Patent No. 430,635, dated June 24, 1890.

Application filed July 20, 1889. Serial No. 318,135. (No model.)

To all whom it may concern:

Be it known that I, DANIEL T. FOX, a citizen of the United States, residing at Independence, county of Montgomery, State of 5 Kansas, have invented a new and useful Invalid's Bed, of which the following is a specification.

This invention relates to that class of invalid-beds the bottoms of which have portions which are adjustable to different angles.

The principal object of this invention consists in a construction whereby the head-section of the bed-bottom is swung or raised to an upwardly-oblique angle on a fulcrum-point which moves back toward the head of the bedstead during the action of raising said section.

Minor objects as to details of construction will appear in the following description and 20 claim.

In the drawings forming a part of this specification, Figure 1 is a plan with parts broken away and parts in section on lines 44 and 55 in Fig. 2, and Fig. 2 is a sectional elevation on line 33 in Fig. 1.

Referring to the lettered parts of the drawings, A is the bedstead, of any desired style.

The bed-bottom is composed of three sections bearing transverse slats m to support 30 the mattress. The central section B is rigidly attached to the inside of the side rails of the bedstead. While this section is rigidly attached to the bedstead, it is also preferably detachable by means of bolts and 35 thumb-nuts e. The head-section D and foot-section C are disconnected from the bedstead, except indirectly, by being jointedly attached or hinged to the rigid central section B. The bed-bottom near the front end of the central 40 section B and below the same is provided with a revoluble shaft I, having a central sprocket-wheel R and end pulleys P. The central section B has an oscillating bar b, pivoted at its upper end thereto, one on each side of the bed. To the lower end of each of these bars b is pivoted one end of a rack a, and these 50 racks are arranged to mesh with the pinions i of the shaft E, Fig. 2. The end of the front section D, which is contiguous to the front

end of the middle section B, is hinged at each side of the bed to the front ends of the racks a.

In making this hinged attachment of the 55 front and middle sections I employ straps c, which are attached rigidly to the front section and are hinged at their free ends to the front end of the racks a, Fig. 2.

The slats m may be provided with springs 60 z or otherwise, as desired.

On the under side of the front end of the front section are attached bows H H. To the upper rear end of these bows is attached the 65 end of the belts S, and from thence these belts contract the under surface of the bows H, pass up over pulleys o in the head-board of the bedstead, and thence down to pulleys P, to which the other end of the belts S are attached.

By means of this construction the operation is as follows: When the shaft I is revolved, the shaft E also revolves through the medium of the sprocket-belt z and wheels F R. During this action the belts S wind up on pulleys 75 P of shaft I and raise up and carry rearwardly or away from the head-board the front end of the head or front section D of the bed-bottom. At the same time this action takes place the then lower end of the front or head 80 section D is carried away from the central section B by the racks a, which racks are carried toward the head of the bed by the pinions i, said racks assuming an inclined position and the bars b swinging forward during 85 said movement, all as indicated by the dotted position of the section D, rack a, and bar b in Fig. 2. By this means the invalid is raised to a sitting posture without crowding said invalid toward the foot of the bed and without crowding the head-section unduly against his back, and more especially against the lower portion of his back, as would be the case if the head-section D was hinged to the middle section directly and was not moved 90 away from said middle section during the upward tilt or movement of said head-section.

The foot-section C is hinged at V to the other end of the middle section by straps d, having open slots inserted onto pivots V. 100 These slots are open, preferably, so that the foot-section will be readily detachable; but it is not necessary that any of the sections be detachable unless it is desired to attach them

to another bedstead. The foot of the bedstead has a revolute shaft I', which shaft has end pulleys P' P'. Belts S' are attached to the foot of the foot-section C, pass over pulleys o' o' in the foot-board of the bedstead, and are attached to and arranged to wind up on the pulleys P' P'. By this means the foot-section C is held to a horizontal angle, Fig. 2, or raised or lowered to an oblique angle, as shown by dotted positions in said figure.

Having thus described my invention, what I claim, and desire to secure by Letters Patent of the United States, is—

15 The combination of a bedstead having the upper pulleys, a shaft journaled to the head of the bed, said shaft having the end pulleys and a central sprocket-wheel, a bed-bottom fixed in said bedstead and having an upwardly-movable head-section, belts attached

to the head-section passed over the upper pulleys and attached to the pulleys of the shaft, a shaft having a central sprocket-wheel and end pinions, said shaft being journaled to the fixed part of the bed-bottom, a chain belt on 25 the sprocket-wheels, the racks pivoted to the head-section meshing with the pinions and forming the movable support for the foot of the head-section, and oscillating bars pivoted at one end to the bed-bottom and pivoted at 30 the other end to the end of the racks, substantially as set forth.

In testimony of the foregoing I have hereunto subscribed my name in presence of two witnesses.

DANIEL T. FOX.
